UNITED STATES PATENT OFFICE

ARTHUR VOELSKOW, OF PIRNA-ZWIESEL, GERMANY, ASSIGNOR TO VEREINIGTE ZWIESELE & PIRNAER FARBENGLASWERKE A. G., OF PIRNA, GERMANY, A CORPORATION OF GERMANY

DESIGN FOR PLATE GLASS

Application filed December 4, 1930. Serial No. 37,880. Term of patent 3½ years.

To all whom it may concern:

Be it known that I, ARTHUR VOELSKOW, a citizen of the German Republic, residing at Pirna-Zwiesel, Germany, have invented a new, original, and ornamental Design for Plate Glass, of which the following is a specification, reference being had to the accompanying drawings, forming part thereof.

Fig. 1 is a top plan view of the glass showing my new design; Fig. 2 is an enlarged detail perspective view thereof.

I claim:

The ornamental design for plate glass, as shown and described.

ARTHUR VOELSKOW.
